Primary Examiner — Wan Laymon

(57) **CLAIM**

The ornamental design for an oral cavity treatment device, as shown and described.

DESCRIPTION

FIG. 1 is a front perspective view of an oral cavity treatment device according to a first embodiment of the new design; FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of an oral cavity treatment device according to a second embodiment of the new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines illustrating portions of the oral cavity treatment device form no part of the claimed design.

1 Claim, 14 Drawing Sheets
